WALTER WRIGHT, OF SAN FRANCISCO, CALIFORNIA.

INDIVIDUAL-LETTER-PRINTING APPARATUS.

1,135,242.

Specification of Letters Patent. Patented Apr. 13, 1915.

Application filed January 9, 1906. Serial No. 295,289.

To all whom it may concern:

Be it known that I, WALTER WRIGHT, a citizen of the United States, residing at San Francisco, in the county of San Francisco and State of California, have invented certain new and useful Improvements in Individual-Letter-Printing Apparatus, of which the following is a specification.

This invention is a printing apparatus for producing imitation typewritten letters, one object of the invention being to provide an apparatus of this character which is simple in construction and effective in operation, and to provide means in such apparatus whereby different names and addresses may be successively and automatically printed upon the letters produced, thus avoiding the irregularity of position and dissimilarity in appearance, as well as the labor involved, when such names and addresses are individually inserted, as heretofore the custom, by printing them in with an ordinary typewriting machine.

In the accompanying drawings: Figure 1 is a plan view of the machine with parts in section; Fig. 2 is a rear end view of the same, with a part of the name and address chain broken off; Fig. 3 is a front end view of the same, with parts of the bed and track in section; Fig. 4 is a longitudinal section of the frame and type bed, with parts in elevation and broken away; Fig. 5 is a side elevation; Fig. 6 is an enlarged vertical section of a part of the paper feed box; Fig. 7 is a top plan view of the apparatus, the inking ribbon and other parts being broken away; Fig. 8 is a perspective sectioned view of the supporting drum for the chain of name plates; Fig. 9 is a similar view showing the name plates diagrammatically in position in their holders; Fig. 10 is a sectional view of the same.

Referring to the drawing, 1 represents a frame supported upon legs 2, and including longitudinal side members marked 3, which serve to confine the reciprocating carriage 4 in place. The center of the frame, beneath the carriage, is formed to receive and support the body form-section 5, which comprises a chase containing the assemblage of type or impression characters that print the body portion of the letter, exclusive of the name and address of the addressee. The latter are printed by a separate form-section, as later described. Over the type passes a broad inking ribbon 6 of the same

general character as used in typewriting machines and of a width equal to or greater than the width of the typed surface. This ribbon is smoothly stretched over a pair of guide-members or rollers 7 mounted in the frame at each end of the chase and wound at both ends upon spools 8 mounted on the frame, which spools are provided with gear wheels 9 at their ends adapted to be intermittently operated by the racks 10 on the reciprocating carriage. The gear wheels 9 are disposed at opposite ends of the two spools as shown in Fig. 1, and there is a rack 10 on each side of the carriage adapted to encounter and rotate each wheel. Both racks appear in the end views of Figs. 2 and 3, as well as in Fig. 1, being there marked 10, as above mentioned. With each gear wheel there is associated in any suitable manner a ratchet or slip joint between itself and the body of its spool as shown in Fig. 1, whereby it will rotate its spool when rotated in one direction by its rack, but will slip idly thereon if rotated by its rack in the opposite direction, and the ratchet teeth on each wheel are appropriately faced (in opposite directions), so that whichever one is operating will draw the ribbon over the type, unwinding it from the other spool. Each ribbon spool 8 is vertically adjustable in slots 11 in the sides of the frame, and may be lowered therein so that its gear wheel 9 will be out of the path of its rack 10, and under such circumstances the ribbon will be advanced by the other spool. The ribbon may thus be moved in either direction, *i. e.*, from either spool to the other, as circumstances may require, the movement in either case being imparted to it by the reciprocating carriage and taking place at or toward the end of the stroke in either direction. I have observed that as the ribbon advances over the type surface of the machine it tends to become exhausted of ink toward the far end of the surface and therefore to print a lighter impression at that end than at the other, and inasmuch as such difference of impression will at once destroy the similarity of the printed letter to an actual typewritten letter, I have provided means for correcting such tendency or reducing it to an extent that will render it unnoticeable. This means is represented by the racks 10, which have a prolonged engagement with their ratchet wheels 9, thereby imparting an extended, or long-step movement to the rib-

bon, so that the ink thereon, between head and foot of the letter, at any given time, is substantially uniform.

The carriage 4 is adapted to move or slide 5 on parallel upper and lower tracks formed in the main frame, so as to pass over the type surfaces supported thereon, being desirably equipped with ball bearings as indicated at 22 and 23, and also with a handle 10 4^a. The balls run in grooves formed in the carriage and tracks respectively and thereby the carriage is confined against lateral displacement so that racks 10 thereon will reliably engage the ribbon feeding mechanism 15 above described. The lower tracks support the weight of the carriage, while the upper tracks hold the carriage down when the impression is being made as will later appear. The carriage carries the boxes 12 for the 20 shaft 13 of the roller platen or pressure-roller 14, said shaft 13 being secured eccentrically to bearings 15 which can revolve in the boxes 12 at each end. To each of said bearings 15 is secured a depending platen-controlling arm 16 which is adapted to encounter and travel upon a track or rail 17 at 25 each side of the main frame. These tracks are so placed as to move the arms to an inclined position when encountered by them, and maintain them in such position for as long as the arms engage the tracks. When the carriage arrives at the end of its path of movement, the end of the arm 16 passes over and drops off the end of the track, so that, 30 when the carriage returns, the arm is moved so as to be inclined in the opposite direction, thereby having been moved through an angle sufficient to turn the eccentric bearings 15 in the boxes to raise the shaft 13 sufficiently to raise the lower side of the pressure-roller, which turns thereon, out of contact with the inking ribbon 6, so that the surface of the roller is not soiled by the ink in its return movement. The boxes 12 are 35 capable of vertical movement in their box frames 19 in the carriage and are adjusted therein by means of screws 20 and opposing springs 21, in such manner as that any yielding of the platen surfaces must take place 40 by virtue of the resilience of the platen itself rather than by yielding of the bearings of the platen shaft, that is to say, the printing pressure is resisted positively by the ends of the screws 20. It will be seen that the two 45 screws 20 are intended to be adjusted so as to maintain the surface of the platen in proper relation to the type surface. The carriage also carries a paper feed box for 50 the supply of paper or letter-heads on which the imitation typewritten letters are to be printed. As will be presently seen, the sheets of paper are successively and automatically advanced from this box on to the top of the inking ribbon and between the 55 same, and the impression roller, being re-

moved from this position as soon as the impression has been made.

The paper feed box 24 is oblique or generally rhomboidal in form, as viewed from the side, so that its pile of contained sheets 70 25 (Fig. 6) lie therein at an angle with the bottom 26 of the box, the top sheet of the pile being normally prevented from slipping from the box by means of a knife-edge lip 27 at the front of the bottom of the box which 75 rises in front of the lower edge of the foremost sheet of paper. The top of the front of the box is also covered, as shown at 28, to prevent the paper falling forward therefrom. The sheets are normally pressed toward the front of the box by a false back or follower 29 having pins 30 sliding in slots 31 in the sides of the feed box, said pins being connected to springs 32 which thereby 80 normally draw said back and the pile of sheets resting against the same, forward toward the front of the box. The top or upper sheet of the pile is thus held pressed against a roller 33, the shaft of which revolves in extensions 34 from the feed box. As the 85 carriage moves from right to left in Fig. 4, a gear wheel 35 upon the shaft of the roller comes into engagement with a rack 36 fixed adjustably upon the rail 3 of the main frame and the shaft and roller are thereby revolved in a left-handed direction, thereby causing the top sheet of paper to be lifted up above the level of the lip 27. When the carriage returns, the roller is revolved in the opposite direction, causing the top sheet of 90 paper to descend and pass over the lip, the next succeeding sheet having in the meantime, by reason of the springs, been pressed close against said lip. Thus at the commencement of the return motion from left to 95 right, the lower edge of said sheet is passed between the impression roller and the inking ribbon which overlies the type surface as above described. The shaft of the impression roller having now been lowered by reason of the timely engagement of the arms 16 with the tracks 17, as above explained, and the eccentrics having thereby been moved through the necessary angle, the impression roller has now been brought into proper 100 printing relation to the inking ribbon and the type surfaces, so that the sheet of paper is nipped and pressed between the roller and the ribbon and type surface. Thus as the carriage moves from left to right the impression roller is rolled over the ribbon and type and a print is thereby made upon the 105 paper through the inking ribbon.

Coming now to the printing of the names and addresses, it will be understood that the 110 name and address must be printed at the head of the body of the letter as printed by the type of the body form-section and in proper marginal alignment with such printed matter, usually in alignment with the 115 120 125 130

left-hand margin thereof. For this purpose the bed of the main frame is provided with an aperture, appearing in Fig. 4 and in the plan views, and in this aperture is mounted 5 a rotary drum or carrier 44 carried on a transverse shaft 41, which is journaled at its ends in the main frame. The drum 44 may be of such length as to occupy the entire width of the aperture, as indicated in 10 Figs. 1 and 7, or it may be of a lesser length, being long enough in any event to accommodate the name and address to be printed. The drum 44 serves as a carrier and movable support for the successive 15 name and address form-sections. The latter in the present case, consist of holders 46 each containing a type surface 43 representing the name and address of the addressee of one of the letters to be printed, such type 20 surface being produced in any suitable manner, and the same alone or in combination with its holder constituting a name and address slug or plate. The drum 44 is provided with a number of flattened sides, four 25 in the present case, which serve as seats or supports for the slugs or address-form sections. These seats are desirably grooved (45) with a key-slot or otherwise formed to coöperate with a rib or corresponding for- 30 mation of the address slug, or the holder 46, so as to receive and accurately position the same, thus bringing the name and address type surface in proper alinement with the type surface of the body of the letter. The 35 successive name and address sections in the present case are linked together in the form of a chain, the links being shown at 42. The chain is initially wound upon or trained over a rotary spool 53 provided with guide 40 flanges at its ends and mounted on a shaft 54 which is subject to the braking friction of a spring 51 shown in Fig. 5. The chain of name and address form-sections is adapt- 45 ed to pass from this spool upwardly to the printing seats on the drum or carrier 44 and as discharged from the printing seat passes downwardly where it may be collect- 50 ed or wound on a second similar spool 55, and the latter may be provided with a 55 spring 50 for winding the chain up upon it as delivered from the carrier 44. The end flanges of the two spools 53 and 55 confine the name and address slugs snugly between them and are so placed as to guide the said 60 slugs into position on the carrier where they will be in proper marginal alinement with one side of the type surface of the body form section.

The carrier 44 for the changeable name 65 and address sections is provided with a number of radially disposed arms 48 equal to the number of its printing seats and arranged thereon in the path of a pawl 47 mounted on the carriage at one side of the type and inking ribbon. In the case, as shown, where

the carrier 44 extends the full width of the frame aperture, arms 48 may be provided at each of its ends and a pawl such as 47 provided on both sides of the carriage, as shown in Fig. 7. Such arrangement is preferable where very long address-form chains are used in order to equalize the strain and shock upon the carriage. The pawl 47 is pivoted to the bottom of the paper-feed box and it will be understood that the arms 48 are so arranged with reference to their respective printing seats that when engaged by the pawl moving toward the rear of the machine, the carrier 44 will be turned one-quarter of a revolution, thereby removing 70 one name and address form section and bringing the next one into the printing position or impression plane. On the return of the carriage the pawl simply rides over the arm without affecting it, as will be obvious. As the carrier 44 turns toward or into the printing position just referred to a spring detent or finger 52 which is secured to the frame at each side, snaps into the ends of the groove 45 thereby determin- 75 ing the correct position of the seat and the address section therein and maintaining the type surface of the latter in coincidence with the printing plane.

In the operation of the machine, a stack 80 of letter heads or sheets of paper, is placed in the paper feed-box 24, so as to be urged forwardly against the holders 28 thereof and the roller 33 as above described. The carriage is then grasped by the handle 4a 100 and moved back and forth in the trackway provided for it, each outward stroke serving to start a single sheet of paper under the impression roller which draws it down and lays it full length over the portion of the 105 ribbon which covers the body and name and address form sections, at the same time making the impression from both of these form-sections through the ribbon. Slightly before the roller reaches the point where the 110 addressee's name is to be printed, the feeding means whereby the address forms are advanced successively into printing position is brought automatically into operation, 115 that is to say, the pawl 47 encounters and rotates the carrier 44, so as to bring the next name plate in position. During such change the name plates, slugs or address forms are brought upwardly from below 120 and in a direction which is transverse to the path of the impression roller and also beneath the inking ribbon which covers the aperture in which the carrier 44 is mounted.

In the drawings the numeral 40 represents 125 a set of ordinary inking rolls which may be used when desired to replenish the ink on the inking ribbon. It will be understood that the drawings do not attempt to illustrate the detail of the mechanical design of 130 my invention.

I claim:—

1. An apparatus of the character described, comprising a frame, type-surfaced means thereon, a carriage reciprocating thereover, a feed box and pressure roller carried by said carriage, and automatic means operated by the movement of the carriage for feeding in succession sheets of paper from the feed box between the pressure roller and the type-surfaced means, substantially as described. 70
2. An apparatus of the character described, comprising a frame, type-surfaced means thereon, a carriage reciprocating thereover, a feed box and a pressure roller carried by said carriage, transfer material over said means, and automatic means operated by the movement of the carriage for feeding in succession sheets of paper from the feed box between the pressure roller and the transfer material, substantially as described. 75
3. In an apparatus of the character described, the combination of a frame, a carriage, an eccentrically mounted shaft, a pressure roller on said shaft, means for reciprocating said carriage over said frame, means for giving a partial rotation to the eccentric shaft to raise and lower the roller alternately to a non-printing or a printing position, a plurality of individually type-surfaced means for printing changeable matter, type-surfaced means on said frame for printing permanent matter, an inking ribbon over both of said type-surfaced means and beneath the pressure roller, and means automatically actuated by the movement of the carriage for intermittently advancing said first named type-surfaced means in succession into the same plane as the second, substantially as described. 80
4. In a printing machine, the combination of a support, a form of type thereon, a rotatable pressure roller, means for moving the pressure roller bodily over the form of type and in coaction with the printing faces thereof, a plurality of address plates, and means for moving said address plates successively in a direction transverse to the direction of movement of the pressure roller and into printing position. 85
5. In an addressing machine, the combination of a bed, an impression roller adapted to bodily travel thereover, and feeding mechanism adapted successively to advance address slugs into printing position thereon in a direction transverse to the path of travel of said impression roller. 90
6. In a machine of the kind described, the combination of a support, a form of type thereon, a rotatable pressure roller, means for moving the pressure roller bodily over the form of type and in coaction with the printing faces thereof, a plurality of address plates, means for moving said address plates successively in a direction transverse to the direction of movement of the pressure roller and into printing position. 95
7. In a machine of the kind described, the combination of a support, a form of type thereon, a rotatable pressure roller, means for moving the pressure roller bodily over the form of type and in coaction with the printing faces thereof, a plurality of address plates, means for moving said address plates successively in a direction transverse to the direction of movement of the pressure roller and into printing position, and a member holding the address plates in printing position. 100
8. In a machine of the kind described, the combination of a support, a form of type thereon, a rotatable pressure roller, means for moving the pressure roller bodily over the form of type and in coaction with the printing faces thereof, a plurality of address plates, means for moving said address plates successively in a direction transverse to the direction of movement of the pressure roller and into printing position, and a spring-yielding member holding the address plate in the printing plane. 105
9. In a machine of the kind described, the combination of a support, a form of type thereon, an ink ribbon overlying the type, a rotatable pressure-roller, means for moving the pressure-roller bodily over the ribbon or type and in coaction with the printing faces of the latter, a plurality of address plates, means for moving the same successively in a direction transverse to the direction of movement of the pressure-roller and into printing position beneath the said ribbon. 110
10. In a machine of the kind described, the combination of a support, a form of type thereon, a rotatable pressure-roller, means for moving the same bodily over the form of type and in coaction with the printing faces thereof, a plurality of address plates, and a member moving with the pressure-roller adapted for moving said address plates successively in a direction transverse to the direction of movement of said pressure roller and into printing position. 115
11. In a machine of the kind described, the combination of a support, a form of type thereon, a rotatable pressure-roller, means whereby the pressure-roller is bodily reciprocated over the form of type in coaction with the printing faces thereof during the printing stroke and removed from such faces during the return stroke, a plurality of address plates and means for moving said address plates successively in a direction transverse to the direction of movement of the pressure-roller and into printing position. 120
12. In an apparatus of the character de- 110

- scribed, the combination of a frame, a carriage, an eccentrically mounted shaft on said carriage, a roller on said shaft, means for reciprocating said carriage over the frame, 5 a plurality of individually type-surfaced means for printing changeable matter, type-surfaced means on said frame for printing permanent matter, an inking ribbon over both of said type-surfaced means and beneath the pressure roller, and means automatically actuated by the movement of the carriage for intermittently advancing said first-named type-surfaced means in succession into the same plane as the second. 10
13. In an apparatus of the character described, the combination of a frame element, a carriage, an eccentrically mounted shaft on said carriage, a roller element on said shaft, means for reciprocating one of the said elements relative to the other, a plurality of individually type-surfaced means for printing changeable matter, type-surfaced means on said frame for printing permanent matter, an inking ribbon over both of said type-surfaced means and beneath the pressure roller, and means automatically actuated by said reciprocating element for intermittently advancing said first named type-surfaced means in succession into the same plane as the second. 15
14. In an apparatus of the character described, the combination of a frame element, a carriage, a pressure roller element on said carriage, means for reciprocating one of the said elements relatively to the other, an eccentrically mounted shaft for said roller, a plurality of individually type-surfaced means for printing changeable matter, type-surfaced means on said frame for printing permanent matter, an inking ribbon over both of said type-surfaced means and beneath the pressure roller, and means for intermittently advancing said first named type-surfaced means in succession into the same plane as the second means. 20
15. In an apparatus of the character described, comprising a frame, a carriage, a pressure roller on said carriage, type-surfaced matter on said frame for printing permanent matter, a plurality of individually type-surfaced means for printing names and addresses, a carrier for said means, a shaft for said carrier, an inking ribbon over said type-surfaced means and beneath the pressure roller, and means actuated through the movement of the carriage for bringing said pressure roller in contact with said type-surfaced matter during its forward movement and for raising said roller out of contact therewith on its return movement. 25
16. In a machine to produce a series of seemingly type-written communications, the combination of a bed having means for fixedly supporting a form to print the body of the letter, a series of address forms movable in succession to proper printing position in relation to the fixed form, and a roller platen movable over both the fixed form and the address form that is in printing position, the address forms having movement through the bed at approximately right angles thereto, to the printing position. 30
17. Apparatus of the kind described, comprising a main form for printing the body of the letter and a changeable form for printing the address, an ink ribbon overlying both said forms, a pressure-roller having printing and return strokes and coacting with said forms and ribbon on the printing stroke, means for separating the roller from the ribbon on the return stroke, and means for advancing address forms successively in a direction transverse to the direction of movement of the pressure-roller and into printing position beneath said ribbon and in the plane of the main form. 35
18. Apparatus for printing simulations of typewritten letters, comprising a frame, type-surfaced form-section for printing the body of the letter and a form-section for printing the address of the letter, a part forming a seat to support the address-printing section in the printing plane of the other section, said part being located between the side margins extended from the type surface of such other section, whereby the address will be printed between the right and left hand margins of the printed matter representing the body of the letter, an ink ribbon for both said form sections, spools for said ribbon on opposite sides of the frame, a pressure roller coacting with the form sections to make the impression through the ribbon upon the paper sheet, means for automatically and successively moving different address-printing sections into the said seat-forming part, and feeding mechanism intermittently operated to advance the ribbon over said form sections, substantially as described. 40
19. Apparatus for printing simulations of typewritten letters, comprising a bed supporting a main type-surfaced form adapted to print the body of the letter and having a recess at one end of said body-printing form, the said recess occupying the space between the side margins of the type-surfaces representing the body of the letter, means for successively introducing different address forms into the said recess, a support to hold the latter form in the printing plane in said recess, an ink ribbon adapted to cover both forms, a pressure roller coacting with both forms to make the impression through the ribbon, spools for the ribbon, and means for rotating said spools between impressions. 45
20. Apparatus of the kind described, comprising in combination a main form section 50

- 6
- for printing the body of the letter, a support for a form adapted to print changeable matter at one end of the body of said main form, means for moving successive forms to printing position on the said support, means for determining the printing position of such form when on the support, a ribbon adapted to cover both forms, a pressure roller traveling bodily over both forms to make the impression from both of them in a single operation, and means for intermittently advancing the ribbon.
21. In a machine of the kind described, the combination with a frame having parallel tracks provided with grooves and type surfaces between the tracks, a carriage supported against vertical movement by said tracks and having anti-friction bearings engaging the grooved tracks and preventing lateral displacement of the carriage, a pressure roller journaled on the carriage, ribbon spools supported one near each end of the tracks and at the ends of the type-surfaces therebetween, means on the carriage for actuating said spools, means whereby the carriage and roller may be moved along the track, and means moving with the carriage for actuating the spools at the end of the carriage travel.
22. In a machine of the kind described, the combination of a horizontal stationary bed, a letter-form thereon, an ink ribbon disposed over the bed and form, means for feeding changeable forms successively into printing position beneath said ribbon and in juxtaposition with said letter form, an impression roller adapted to travel over the ribbon and a paper sheet thereon, to take an impression from both forms in one operation, and a device for operating said feeding means during the printing stroke and before the end of said stroke.
23. In a machine of the kind described, the combination of a bed, an impression roller adapted to travel bodily thereover, and feed mechanism actuated by said traveling roller for successively placing address plates in printing position with respect to the bed, an ink ribbon, and means for imparting a long-step feed to said ribbon between impression strokes of said roller.
24. In a machine of the kind described,
- the combination of a bed, an ink ribbon disposed thereover, spools at opposite ends of said bed, on which the ribbon winds and unwinds, one of said spools having a ratchet, feed mechanism for successively placing address plates in printing position with respect to the bed beneath said ribbon, an impression roller adapted to travel bodily over the said ribbon and the address plate beneath the same, and an actuating member moved by said traveling roller, adapted to coöperate with said ratchet.
25. In an apparatus of the kind described the combination of a bed, a form thereon, a pressure-roller making more than a complete revolution in coöperation with said bed, an ink ribbon interposed between the roller and the form, means in fixed relation to the axis of the roller for supporting a plurality of sheets of paper and placing them, one after another, automatically upon the ribbon, and means for intermittently advancing the ribbon.
26. In apparatus of the kind described, a bed or frame supporting a main form of type and having a recess therein to receive successive forms each adapted to print different matter, an impression roller coacting with both forms and having its axis parallel with the lines of type of both forms, an ink ribbon between said forms and the impression roller, means for successively advancing forms to printing position in said recess and means for imparting a long-step movement to the ink ribbon between impressions.
27. In apparatus of the kind described, the combination of a main form, a changeable form, means for changing the changeable form, a ribbon covering both forms, a pressure roller coacting with both forms, a frame therefor, a paper supply on such frame, means for automatically feeding single sheets from such supply between the ribbon and the pressure-roller, and means for advancing the ribbon over both forms.
- In witness whereof I have hereunto set my hand in the presence of two subscribing witnesses.
